PREVENTION OF HYDROGEN FIRES
IN CHLORINE CELLS

Marvin L. Moore, Mentor, Ohio, and Phillip H. Sears, Houston, Tex., assignors to Diamond Shamrock Company, Cleveland, Ohio, a corporation of Delaware

ABSTRACT OF THE DISCLOSURE

Hydrogen fires in diaphragm-type chlorine cells are prevented by providing a chemically-inert, non-conducting, non-wetting, annular insert in the hose which connects the hydrogen header with the cell can.

BACKGROUND OF THE INVENTION

A common problem in cell rooms containing a large number of diaphragm-type cells for the production of chlorine and caustic is the occurrence of hydrogen fires. In these cell rooms, hydrogen outlets extend from the individual cell cans and are connected to the hydrogen header, usually by means of flexible natural rubber hoses. Hydrogen fires are believed to be caused by electrical shorting through the caustic soda-salt bridge which deposits on the inner wall of the rubber hose. These hydrogen fires naturally occur most frequently on cells having the highest voltage to ground. In addition to the obvious hazard of these fires to personnel and equipment in the cell room, there is the not insubstantial problem of failure of the rubber hoses, the replacement of which adds considerable expense to the operation of the cell room.

While a number of solutions have been proposed to end this problem, such as forming these hoses entirely from a non-wetting material, these solutions have proven to be too expensive for commercial application.

STATEMENT OF THE INVENTION

Therefore it is the primary object of this invention to provide an economical and effective means for preventing hydrogen fires in diaphragm-type cells.

This and further objects and advantages of the present invention will become apparent to those skilled in the art from the description and claims which follow.

It has now been found that hydrogen fires resulting from the formation of caustic soda-salt bridges in the hoses connecting diaphragm cells with hydrogen headers may be substantially completely prevented by the provision in the hoses of annular inserts of a chemically-inert, non-conducting, non-wetting material.

DESCRIPTION OF THE PREFERRED EMBODIMENTS

As is set forth hereinabove, it is believed that the primary cause for the hydrogen fires which occur in diaphragm-cell operation is the formation of electrically conductive caustic soda-salt bridges between the hydrogen header and the cell can. These salt bridges result from the deposition of the various salts present in the catholyte on the inside of the rubber hoses. The formation of this caustic soda-salt bridge can then lead to electrical shorting between the cell and the grounded header. Surprisingly, it has been found that the formation of these salt bridges may be prevented by the provision in the connecting hose of as little as a two inch annular insert of a

2

chemically inert, non-conducting, non-wetting material. With the prevention of these salt bridges, and consequently the prevention of hydrogen fires, not only is the hazard to personnel and equipment removed, but also a considerable savings is realized in that the connecting hoses need not be replaced as often.

In order to illustrate the practice of the present invention, several test cells which previously have been particularly susceptible to hydrogen fires are provided with modified connecting hoses according to the practice of the present invention. These test cells previously had an average hose life of from 5-6 days with a range of from 0.5 to 10 days. Each of the connecting hoses, which have an internal diameter of 3.25 inches, is fitted with a two inch wide annular insert which consists of sections of polytetrafluoroethylene tubing having an external diameter of 3.25 inches and a wall thickness of 0.08 inch. These inserts are located in the hose approximately two to three inches below the nozzle from the hydrogen header. In all instances the inserts completely eliminate hydrogen fires on the test cells and the hoses do not fail after a service life of from 70-93 days.

It has been estimated that in a cell room currently requiring 1,400 replacement hoses per year, only 1,000 hoses per year will be required if the cells normally subject to hydrogen fires are provided with the annular inserts of the present invention. The only reason for replacing the hoses will then be that chemical deterioration of the rubber has taken place.

A number of materials are useful according to the present invention for fabricating the annular inserts, the primary consideration being that these materials are chemically-inert, non-conductive and non-wetting. Examples of such compounds are polytetrafluoroethylene and polyvinyl-fluoride. It will be obvious to those skilled in the art that, while chemical inertness is extremely desirable, a certain amount of instability can be tolerated if the annular inserts are periodically discarded.

Although the invention has been described with reference to certain preferred embodiments thereof, it is not to be so limited since changes and alterations may be made therein which are within the full and intended scope of the appended claims.

What is claimed is:

1. In a method of operating an electrolytic diaphragm cell which includes a cell can, a hydrogen header and a hose of wettable material connecting said can and header the improvement comprising, providing said hose with an annular insert engaging the inner wall thereof, said insert being composed of a chemically-inert, non-conducting, non-wetting material, whereby hydrogen fires are substantially prevented.

2. A method as in claim 1 where the annular inert comprises polytetrafluoroethylene.
